UNITED STATES PATENT OFFICE.

JULIAN J. McMURTRY AND EARL V. McMURTRY, OF SAN FRANCISCO, CALIFORNIA.

PAPER-BOX-TAPING MACHINE.

1,274,065.

Specification of Letters Patent. Patented July 30, 1918.

Application filed November 21, 1917. Serial No. 204,280.

To all whom it may concern:

Be it known that we, JULIAN J. McMURTRY and EARL V. McMURTRY, citizens of the United States, and residents of the city and county of San Francisco and State of California, have jointly invented a new and useful Improvement in Paper-Box-Taping Machines, of which the following is a specification.

10 Our invention relates to improvements in paper box taping machines wherein duplicate taping mechanisms operate in conjunction with improved means for adjusting the distance between said duplicate mechanisms 15 to insert and secure the ends of separate tapes or the ends of a single tape through a paper box blank at two separate points; and the objects of our invention are

First, to provide an improved device 20 adapted to secure the ends of a tape or tapes to a paper box blank;

Second, to provide improved duplicate means for taping paper box blanks whereby said blank may have tape ends secured 25 thereto at two different points; and

Third, to provide means for adjusting the space or distance between the duplicate taping mechanisms to accommodate said distance to the length of a single tape to be 30 used for a handle or carrying means, or for two separate tapes whereby various sizes of blanks may be taped.

We accomplish these several objects by means of the device disclosed in the drawings forming a part of the present specification wherein like characters of reference are used to designate similar parts throughout the said specification and drawings, and in which—

40 Figure 1 is a broken front elevation of our improved device;

Fig. 2 is a transverse vertical sectional view partly broken, taken on line 2—2 of Fig. 1 of the drawings in the direction indicated;

Fig. 3 is an enlarged sectional view, partly broken, taken on line 3—3 of Fig. 2 in the direction indicated;

Fig. 4 is an enlarged vertical sectional view taken through the gluing or adhesive applying mechanism;

Fig. 5 is a plan view of Fig. 4 disclosing also the mechanism for pressing the tape end onto the applied adhesive; and

55 Fig. 6 is a side elevation of Fig. 5.

Referring to the drawings the numeral 1 is used to designate in general a main frame having a vertically disposed back plate 2 provided with a horizontally disposed slot 3 near the upper portion thereof and a series of vertically disposed parallel slots 4 having supports 6 slidably mounted therein to support various sizes of paper box blanks 7 against the plate 2 and over the horizontal slot 3 therein.

The lower portion of the main frame 1 is provided with securing rods or struts 8 to impart rigidity to said lower portion of said main frame 1. Parallel threaded shafts 9, oppositely threaded from the center toward opposite ends, are rotatably mounted within the main frame 1 and are provided with sprockets 11 connected by a chain 12 whereby said threaded shafts 9 may be rotated simultaneously.

Duplicate adhesive applying, tape inserting and tape pressing or securing means are mounted upon the threaded shafts 9, each unit consisting of vertically disposed parallel subframes 14 uniting near the upper portion of the plate 2 and in the rear thereof, to support a glue or adhesive pot or container 16 having an inclined adhesive spreader 17 therein, the purpose of which will hereinafter be more fully set forth. A lever 21 is pivotally mounted between the subframes 14 of each unit as at 22 and extends upward back of the plate 2 to a point adjacent the adhesive container 16. The lower end of each lever 21 is provided with an anti-friction roller 23 which is engaged by a cam 24 on a sleeve 26 mounted between the lower portions of the parallel subframes 14 and feathered to a power shaft 27 rotatably mounted within the main frame 1.

The upper end of the lever 21 has pivotally connected thereto one end of a link 29 the other end of said link being provided with a roller 31 which normally rests within the adhesive within the container 16 and is moved to spread and distribute the adhesive over the inclined spreading or distributing surface 17 and thereafter move through the horizontal slot 3 in the plate 2 and deposit a portion of the adhesive onto the back of the paper box blank 7.

Each unit or subframe 14 is further provided with a vertically disposed standard 32 which extends upwardly and in front of

the plate 2 to a point opposite the container 16 in the back of said plate 3.

Slidably mounted within the upper end of the standard 32 is a taping needle 33 of the usual type having an inclined slot 34 in the end thereof. A stem 36 of a presser foot 37 is also slidably mounted in the upper portion of the standard 32 and immediately below the needle 33. The stem 36 of the presser foot 37 is provided with a rigid collar 38 and a loose collar 41 and a spring 39 is interposed between the two collars.

A bell crank lever 42 is pivotally mounted as at 43 to the standard 32 and is operatively connected, by means of a link or connecting rod 44, to an operating rod 46 slidably mounted within suitable bearings 47 of the standard 32. The lower end of the rod 46 is provided with a roller 48 which is engaged by a cam 49 on the sleeve 26 feathered to the power or driving shaft 27.

A spring 51 is interposed between a rigid collar 52 on the rod 46 and the upper bearing 47 for said rod and operates to retain contact between the roller 48 and the cam 49 on the sleeve 26.

Each sleeve 26 is further provided with a bevel gear 53 meshing with a second bevel gear 54 on the counter shaft 56 rotatably mounted within each unit or subframe 14. The other end of each counter shaft 56 is also provided with a bevel gear 57 which meshes with a bevel gear 58 on the lower end of a vertically disposed shaft 59 having its upper end rotatably held in a suitable bearing 61 on each adhesive container 16.

The top of each shaft 59 is provided with an arm 62 having a roller 63 thereon to engage and move a lever 64 pivotally mounted within a suitable bearing 66. The free end of each lever 64 is operatively connected to a parallel bell crank 67 pivotally mounted as at 68 within a slide 69 mounted within guide ways 71 formed on the adhesive container 16.

The parallel bell crank levers 67 are provided with a roller 73 adapted to be moved or rolled within the slot 3 of the plate 2 and against the back of the paper box blank 7 to press the projected ends of the tape, not shown, onto the previously applied adhesive when the lever 64 is moved in one direction and to be held away from said paper box blank 7 in the return direction.

55 The operation is as follows:

The blank paper box, in a knock down condition, is placed on the supports 6 slidably mounted within the vertical slots 4 of the plate 2 so that the points through which the tapes are to be inserted lie directly over the horizontal slot 3.

The subframes 14 are moved toward or away from each other to bring the tapering needles 33 opposite the points where the tape 65 is to be inserted by rotating the threaded

parallel rods 9 by means of the handle 73 attached to one of the rods, or by any other suitable means.

As the rods are connected by the chain 12 and sprockets 11 it is obvious that when both rods are rotated the subframes 14 will be moved, by means of the oppositely threaded ends of said rods 9, either toward or away from each other according to the direction of rotation of said rods and the threads 75 thereon.

When the needles 33 have been properly aligned the rotation of the power shaft 27 will rotate the sleeves 26, which are feathered to said power shafts 27, and cause the cams 24 to engage the rollers 23 and operate the levers 21 to move the rollers 31 up the inclined adhesive spreaders or disturbers 17 and into the slot 3 and against the back of the paper box blank 7 thereby depositing 85 adhesive on the back of said blank at the points adjacent to where the tape is to be inserted. As the cam releases the roller 23 a spring 76 secured to each lever 21 and each subframe 14, returns said levers and rollers 90 31 to their respective containers 16.

A continued rotation of the power shaft 27 will cause the sleeves 26 to bring the cams 49 into operative relation with the rollers 48 on the rods 46 thereby operating the 95 needles 33 to carry tape ends through the paper box blank 7, and through the slot 3 at points adjacent the applied adhesives.

The relative position of the needle 33 to the adhesive applying rollers 31 is disclosed 100 in Fig. 5 of the drawings.

As the needle 33 advances toward the blank 7 the stem 36 of the presser foot 37 is engaged by the bell crank lever 42. As the presser foot 37 is positioned in advance of the needle 33 it is evident that said presser foot will first engage the blank 7 and the continued movement of the lever 42 will be permitted by the compression of the spring 39, said spring operating to retain the blank 110 7 against the plate 2 until the needle 33 is withdrawn therefrom after having passed the tape end through said blank 7.

The cams 49 are adapted to permit a quick return of the needles 33 so that the friction 115 of the card board blank 7 will strip the tape ends from the slots 34 of the needles 33, each presser foot 37 operating to retain the blank 7 against the plate 2 until the needles have been withdrawn.

The continued rotation of the power shaft 27 will rotate the gears 54, 57 and 58 and the rods 59 to cause the arms 62 and rollers 63 thereon to engage the levers 65 and to move said levers toward the adhesive container 16.

As the levers 64 move forward the action or movement thus transmitted to the bell crank levers 67 will first move the rollers 73 into the slot 3 and against the blank 7 and 130

then along said blank to engage the inserted ends of the tapes and press said ends against the previously applied adhesives.

The return movement of the lever 64, 5 which is facilitated by the coil spring 77, first operates the bell crank levers 67 to move the rollers 73 away from the applied tape ends on the back of the blank 7, until the shorter ends or arms of said levers 67 10 engage the stops 79 on the backs of the slides 68 when the continued movement of the lever 64 will return the slides 69 to normal position as disclosed in Fig. 5 of the drawings.

The blank 7 is then removed and another 15 blank inserted in its place and the above described process is repeated.

It is obvious from the foregoing that we have provided an improved machine adapted to secure tape ends to paper box blanks as 20 well as improved means for adjusting the distance between the points where said tapes are to be secured.

Having thus described our invention what we claim as new and desire to secure by Letters Patent is—

1. A taping machine comprising a suitable frame; adjustable means secured to the frame to retain a paper box blank to be taped; means for applying adhesive at two 30 points on the blank; means for inserting the ends of two separate tapes through the blank adjacent the applied adhesives; and means for pressing the ends of the tapes onto their respective adhesives; and means for varying 35 the space between the adhesive, tape inserting and tape pressing means.

2. A taping machine comprising a suitable main frame; a pair of subframes mounted to move on the main frame; means for 40 retaining a paper box blank to be taped; means mounted upon each subframe for applying adhesive to the box blank at two separate points; means mounted upon each subframe for inserting the end of a tape 45 through the box at a point adjacent the respective adhesive; means mounted upon each frame for pressing the end of the respective tape onto the respective adhesive; and means for moving the subframes away from and toward each other to adjust the space between 50 the tapes.

3. A taping machine comprising a suitable main frame; a pair of threaded shafts rotatably mounted within the frame, said 55 shafts each being threaded in opposite directions on opposite ends; a power shaft rotatably mounted within the main frame; a pair of subframes mounted upon the threaded shafts whereby said subframes may be 60 moved in opposite directions when the threaded shafts are rotated; means mounted within each subframe and operatively connected to the power shaft to apply an ad-

hesive to a paper box blank at two separate 65 points; means mounted within each subframe and operatively connected to the power shaft to insert the end of a tape through the blank adjacent one of the applied adhesives; and means mounted upon each subframe and operatively connected to 70 the power shaft to press the end of one of the tapes onto its respective adhesive.

4. A taping machine comprising a suitable main frame; a pair of threaded shafts rotatably mounted within the frame, said 75 shafts each being threaded in opposite directions on opposite ends; a power shaft rotatably mounted within the main frame; a pair of subframes mounted upon the threaded shafts whereby said subframes may be moved in 80 opposite directions when the threaded shafts are rotated; means mounted within each subframe and operatively connected to the power shaft to apply an adhesive to a paper box blank at two separate points; means 85 mounted within each subframe and operatively connected to the power shaft to insert the end of a tape, through the blank adjacent one of the applied adhesives; and means mounted upon each subframe and operatively connected to the power shaft to press the end of one of the tapes onto its 90 respective adhesive; and means for rotating the threaded shafts simultaneously to move the subframes toward or away from 95 each other.

5. A taping machine comprising a suitable main frame; a vertically disposed plate secured to the main frame and having a longitudinally disposed slot therein; adjustable 100 means for holding a paper box blank on the plate and over the slot; a power shaft rotatably mounted within the main frame; a pair of shafts rotatably mounted in the main frame and threaded in opposite directions 105 from the center toward the ends of said shafts; a pair of subframes mounted upon the threaded shafts, one on each side of the center of said shafts; means mounted upon each subframe for applying an adhesive 110 onto the blank and through the slot in the plate; means mounted upon each subframe for inserting the end of a tape through the blank at a point adjacent one of the applied adhesives; means mounted upon each subframe for pressing the respective tape end onto the respective adhesive; means slidably 115 mounted upon the power shaft for operating the adhesive applying means, the tape inserting means and the tape pressing means; 120 and means for moving the operating means on the power shaft with the subframes.

In witness whereof we hereunto set our signatures.

JULIAN J. McMURTRY.
EARL V. McMURTRY.
